DESIGN FOR A TOY DOG OR THE LIKE

Horace A. Mauney, Lincolnton, N. C.

Application June 18, 1946, Serial No. 130,831

Term of patent 14 years

(Cl. D34—2)

To all whom it may concern:

Be it known that I, Horace A. Mauney, a citizen of the United States, residing at Lincolnton, in the county of Lincoln and State of North Carolina, have invented a new, original, and ornamental Design for Toy Dog or the like, of which the following is a specification, reference being had to the accompanying drawing, forming part thereof.

I claim:

The ornamental design for a toy dog or the like, as shown.

HORACE A. MAUNNEY.
